UNITED STATES PATENT OFFICE

MAX SKLOVSKY, OF MOLINE, ILLINOIS, ASSIGNOR TO DEERE & COMPANY, OF MOLINE, ILLINOIS, A CORPORATION OF ILLINOIS

ROTARY FURNACE

Application filed November 10, 1927. Serial No. 232,266.

My invention relates to heating furnaces of the rotary type comprising a rotating table that constitutes the bottom of the heating chamber and is caused to rotate by suitable driving mechanism, usually in the form of gearing operated from a suitable source of power. In such furnaces it is necessary to provide means for sealing the furnace against the escape of hot gases from the heating chamber, and my invention is particularly concerned with the provision of improved means for effecting such sealing.

The types of seals heretofore used have principally been of two kinds, known as the water seal and the sand seal, in both of which the sealing is effected by means of an annular rim secured to the rotating member of the furnace and extending downwardly and revolving in an annular trough that is kept filled either with sand or with water into which the rim dips, thereby preventing air or gases from passing around the margin of the rotating member. Both these forms of seals are objectionable for various reasons. In the case of the sand seal, the sand is apt to cake, making the rotation of the table difficult, and besides the frictional engagement of the rim with the sand particles makes the draft heavy and increases the expense of operation. Also, the sand is apt to spill out to a greater or less extent and must be replenished from time to time. In the case of the water seal, there is also considerable spilling of the water and it is subject to vaporization and leakage, making frequent replenishment necessary. Also, the danger of freezing when the furnace is not in operation increases the cost of maintenance. In addition to the above types of seals it has also been proposed to use an air seal, but the latter form of seal is not efficient because it is difficult to make it tight enough, and with the use of such air seal the bottom of the furnace is heated excessively, which is objectionable. This form of seal also requires excessive clearance, which is uneconomical.

The object of my invention is to avoid the objectionable features of the above-mentioned types of seals, and to provide one

that will operate efficiently under practically all conditions with a minimum amount of attention, which object I accomplish by providing a seal in the form of a plurality of rings or plates, having surface contact with each other, in the form of laminations, part of such rings or plates being secured to the rotating element of the furnace, and the rest being secured to a suitable stationary part of the furnace, the arrangement being such that the plates carried by the rotating element slide over the surfaces of the adjacent stationary plates. The contact between the relatively moving plates is made close enough to prevent the passage of gases between them, but they do not engage tightly enough to interfere objectionably with the rotating member of the furnace. Preferably, the contacting surfaces are lubricated with graphite or some other suitable material, which reduces friction and also improves the seal. It will be evident that by mounting such a sealing device between the rotating member of the furnace and the furnace wall or some other suitably located stationary support, the heating chamber may be effectually sealed. Such a sealing device may be easily and cheaply installed, and will operate efficiently with little expense for maintenance. The overlapping rings or plates are preferably made flat, but they may be curved or annular in cross-sectional contour, and may be disposed either horizontally, vertically, or in an inclined position, as may be preferred.

In the accompanying drawings, in which I have shown my invention embodied in a seal in which flat plates horizontally disposed are employed:

Figure 1 is a vertical cross-section of part of a rotary furnace illustrating my improved seal;

Figure 2 is an enlarged sectional detail showing more clearly the overlapping elements of the seal and the supporting devices therefor;

Figure 3 is an enlarged sectional detail showing the connecting devices by which the stationary members of the seal are supported; and

Figure 4 is a partial inverted plan view showing one form of driving mechanism for rotating the rotatable member of the furnace.

Referring to the drawings,—5 indicates the side wall of the furnace, and 6 the arch that extends over and forms the ceiling of the heating chamber 7. 8 indicates a rotatable member that constitutes the bottom of the heating chamber. In the construction shown said member is mounted on the upper end of a shaft or pedestal 9 that is provided with a gear 10. A pinion 11 meshes with said gear and is driven by means of a shaft 12 on which it is mounted. In the arrangement shown in Fig. 4 the shaft 12 also carries a spiral gear 13 which is driven by a worm 14 on a shaft 15 arranged to be actuated from any suitable source of power. The mechanism shown for rotating the member 8 may, of course, be varied, as any other mechanism suitable for the purpose may be employed.

In the illustrated construction I provide a fixed support for the stationary elements of the seal in the form of an annular plate 16 that is secured to the lower margin of the side wall 5 in any suitable way, as by bolts 16^a, and extends horizontally toward the axis of the table or bottom 8, which is provided with a downward extending annular flange 17 disposed co-axially with the shaft 9 and forming a pocket to receive the upper end of said shaft. The plate 16 preferably contacts with the peripheral portion of the flange 17, as shown in Fig. 1, and, therefore, forms a closure for the lower portion of the frame.

My improved seal is best shown in Fig. 2, from which it will be seen that it comprises a series of annular rings or plates 18 in spaced relation to each other that are secured to and project radially from the lower central portion of the table 8. As best shown in Fig. 1, said table is cut away on its under side from its margin to a point near the flange 17, thereby forming an annular shoulder 19. To the under surface of this shoulder is secured an annular plate 20, preferably by bolts 21, and on the upper surface of the projecting portion of the plate 20 are mounted the rings 18, said rings being spaced apart by spacers 22 mounted on bolts 22^a that firmly secure the several rings 18 to the plate 20, as best shown in Fig. 2. The spacers 22 and bolts 22^a are located adjacent to the shoulder 19 so that the rings 18 project to a considerable extent beyond said spacers.

Extending into the spaces between adjoining plates 18 are a series of annular rings or plates 23 that are secured in spaced relation to each other on a stationary annular plate 24 mounted on the stationary support 16. As shown in Fig. 2, the rings 23 are spaced apart by spacers 25 and are secured

to the plate 24 by bolts 26, the spacers 25 being of the same thickness as the spacers 22, so that consecutive rings 23 will fit between the several consecutive rings 18 in the manner shown in said figure. In the illustrated construction the plate 24 is secured to the plate 16 by means of an annular angle iron 27 riveted to the outer marginal portion of the plate 24 by rivets 28, as shown in Fig. 3, and secured by rivets 29 to an annular angle bar 30 secured by bolts 31 to the plate 16. The considerable radial span of the plate 24 between the angle iron 27 and the rings 23 results in this portion of said plate having more or less flexibility, thereby constituting a flexible attaching means between the furnace wall 5 and the series of plates 23. Such accommodates any slight variations of height which may tend to occur between the two series of plates by reason of thermal expansion, and also avoids the necessity of accurate fitting or mounting of the plates in the assembly thereof. As best shown in Fig. 1, the angle bar 30 is located a short distance from the wall 5 of the furnace to provide a scale pocket 32 between said angle bar and the furnace wall.

The connections between the plates 16 and 24 are made tight so that gases can not pass the outer portion of the plate 24, and by reason of the surface contact between the plates 18 and 23 gases can not pass between such plates. Therefore, the heating chamber is effectually sealed. In Fig. 2 the several plates 18 and 23 are shown somewhat separated from each other, but it will be understood that they are intended to make sufficiently close contact to form a seal, and as has been explained they may be covered with graphite or any other suitable lubricant to further perfect the seal. It will be noted that the two series of plates 18 and 23 provide, in effect, a laminated assembly of rotating and stationary cooperating sealing members.

It will be evident that although the plates 18 are secured to the bottom or table 8 through the plate 20, and therefore rotate with it, and the plates 23 being secured to the stationary plate 24 remain stationary, there will always be an extended surface contact between the rotating and stationary plates which will effectually seal the heating chamber. The number of sealing plates used may vary considerably, and preferably an equal number of stationary and rotating plates are provided, although that is not essential. Also, it will be evident that instead of arranging the sealing plates horizontally as shown they may be otherwise disposed so long as extended cooperating sealing surfaces are provided.

What I claim as my invention and desire to secure by Letters Patent, is:—

1. A sealing device for rotating furnaces,

- comprising a plurality of relatively movable continuous circular plates having extended surfaces in sealing contact with each other, and flexible supporting means cooperating with said plates.
5. 2. A sealing device for rotating furnaces, comprising rotating and stationary plates having extended surfaces of continuous circular form in sealing contact with each other, and flexible supporting means for one of said plates permitting rising and falling movement thereof.
10. 3. The combination with a rotary furnace comprising a wall and a rotating table constituting a heating chamber, of a sealing device comprising a plurality of plates in overlapping laminated relation to each other, having gas tight connection respectively with said table and the furnace wall, said plates having extended surfaces in sealing contact with each other.
15. 4. The combination with a rotary furnace comprising a wall and a rotating table constituting a heating chamber, of a sealing device comprising a set of plates in spaced relation to each other having gas tight connection with the table, and a set of plates in spaced relation to each other having gas tight connection with the furnace wall, said sets of plates being arranged to overlap each other and having extended surfaces in sealing contact with each other.
20. 5. The combination with a rotary furnace comprising a wall and a rotating table constituting a heating chamber, of a sealing device comprising a set of radially disposed plates secured in spaced relation to each other to the under side of said table, and a set of radially disposed plates in spaced relation to each other disposed below said table and having gas tight connection with the furnace wall, said sets of plates being arranged to overlap each other and having extended surfaces in sealing contact with each other.
25. 6. The combination with a rotary furnace comprising a wall and a rotating table constituting a heating chamber, of a sealing device comprising a set of plates in spaced relation to each other having gas tight connection with the table and rotating therewith, and a set of plates in spaced relation to each other having gas tight connection with the furnace wall, said sets of plates being arranged to overlap each other and having extended surfaces in sealing contact with each other.
30. 7. The combination with a rotary furnace comprising a wall and a rotating table constituting a heating chamber, of a sealing device comprising a set of radially disposed plates secured in spaced relation to each other to the under side of said table and rotating therewith, and a set of radially disposed plates in spaced relation to each other disposed below said table and having gas
- tight connection with the furnace wall, said sets of plates being arranged to overlap each other and having extended surfaces in sealing contact with each other.
35. 8. The combination with a rotary furnace comprising a wall and a rotating table constituting a heating chamber, of a sealing device comprising a set of plates in spaced relation to each other having gas tight connection with the table and rotating therewith, and a set of plates in spaced relation to each other having gas tight connection with the furnace wall, said sets of plates being arranged to overlap each other and having extended surfaces in sealing contact with each other.
40. 9. The combination with a rotary furnace comprising stationary enclosing means, rotating table means, a plurality of stationary plates, a plurality of movable plates overlapping said stationary plates, one set of said plates being connected with one of the aforesaid means, and a flexible attachment between the other set of plates and the other of the aforesaid means, both sets of plates coacting to form a gas tight connection respectively with said stationary enclosing means and said rotating table means.
45. 10. The combination with a rotary furnace comprising stationary enclosing means, rotating table means, a stationary plate, a movable plate, one of said plates overlapping the other, one of said plates being connected with one of the aforesaid means, and a flexible attachment between the other plate and the other of the aforesaid means, both of said plates coacting to form a gas tight connection respectively with said stationary enclosing means and said rotating table means.
